WELL PUMP

Jesse E. Hall, Bakersfield, Calif.

Application March 23, 1936, Serial No. 70,361

15 Claims. (Cl. 103—179)

This invention relates to pumps and relates more particularly to well pumps. A general object of the present invention is to provide a practical, simple and particularly efficient deep well pump.

Another object of this invention is to provide a well pump that is operable to pump liquid from a deep well such as an oil well, and to pump or draw gas from the well with such liquid in desirable or regulable quantities.

Another object of this invention is to provide a well pump that does not embody stationary or standing valves liable to become sanded up or made inoperative by accumulations of sand and other solid matter.

Another object of this invention is to provide a practical well pump that includes only two valves both of which travel or move with the reciprocating element of the pump and, therefore, do not become sanded up.

Another object of this invention is to provide a well pump in which the reciprocating element or plunger is under imposed fluid pressure or a hydraulic head during its entire movement which prevents lost motion in the rod and increases the efficiency of the pump.

Another object of this invention is to provide deep well pumping apparatus comprising two or more pumps of the character mentioned above, operated by a single operating rod or sucker rod within a single tubing. The present invention contemplates the provision of two or more pumps of the character mentioned when the depth of the well makes it impractical to employ a single pump and the several pumps are such that they may be arranged on a single oil tubing to pump therethrough and to be operated by a single sucker rod.

Another object of this invention is to provide well pumping apparatus of the character mentioned that is such that the two or more pumps may be readily run into and pulled from the tubing without removing the tubing from the well.

Another object of this invention is to provide a deep well pump of the character mentioned that may be easily lifted from its support or seat to permit the oil tubing to be circulated or flushed out.

Another object of this invention is to provide a well pump that may be successfully operated to pump a relatively large amount of gas and a relatively small amount of oil from a well in which the gas production predominates without producing undesirable gas locks in the pump.

Another object of this invention is to provide

a pump of the character mentioned in which the inlet is constantly reciprocating preventing the accumulation of bodies of sand and shale which may be drawn into the pump, which reciprocation of the inlet also breaks up foreign matter in the well liquid and works a large percentage of the gas out of the oil before it enters the pump.

A further object of this invention is to provide a well pump in which the emulsifying of the pumped liquid in the pump and oil tubing is reduced or materially lessened.

The various other objects and features of my invention will be fully understood from the following detailed description of typical preferred forms and applications of the invention, throughout which description reference is made to the accompanying drawings, in which:

Fig. 1 is a side elevation of a pump of the present invention arranged in operating position in a well, the tubing and protective shell appearing in vertical cross section. Fig. 2 is an enlarged longitudinal detailed sectional view of the pump being a view taken substantially as indicated by line 2—2 on Fig. 1. Fig. 3 is an enlarged longitudinal detailed sectional view of the intermediate portion of the pump being a view taken as indicated by line 3—3 on Fig. 1. Fig. 4 is an enlarged longitudinal detailed sectional view of the lower portion of the pump being a view taken as indicated by line 4—4 on Fig. 1. Fig. 5 is an enlarged transverse detailed sectional view taken as indicated by line 5—5 on Fig. 2. Figs. 6 and 7 are enlarged transverse detailed sectional views taken as indicated by lines 6—6 and 7—7, respectively, on Fig. 3. Fig. 8 is an enlarged fragmentary vertical detailed sectional view of the valve assembly. Fig. 9 is a side elevation of a form of the invention embodying two pumps. Fig. 10 is an enlarged fragmentary longitudinal detailed sectional view taken substantially as indicated by line 10—10 on Fig. 9. Fig. 11 is an enlarged fragmentary vertical detailed sectional view taken as indicated by line 11—11 on Fig. 9.

Fig. 12 is a sectional diagrammatic view of the pump illustrated in Figs. 1 to 8, inclusive, and Fig. 13 is a sectional diagrammatic view of the pump means illustrated in Fig. 9.

The improved pump of the present invention is adapted for the pumping of oil wells and other deep wells and when a well is very deep it is advisable to employ two or more of the pumps to operate in unison or on a single pump rod. I will first proceed with a detailed description of a single pump as employed in the pumping of an oil well or the like, and will then describe the

manner in which two or more pumps may be used in pumping a well.

The well pump of the present invention illustrated in Figs. 1 to 8, inclusive, and Fig. 12 of the drawings includes, generally, a barrel 10 and a plunger 11 related for relative reciprocation, a lower valve 12 carried by the plunger 11, an upper valve or carrying valve 13 on the plunger 11, and other parts, the details and functions of which will be hereinafter described.

The barrel 10 and the plunger 11 are telescopically related for relative reciprocation. It is preferred to support the barrel 10 on a tubing T in a well and to reciprocate the plunger 11 in the barrel to effect the pumping action, it being understood that the plunger 11 may be normally held stationary and the barrel reciprocated, if desired. The barrel 10 is an elongate tubular structure adapted to be removably secured or fitted in the lower end portion of the string of tubing T. The barrel 10 is preferably sectional comprising an upper section 14 and a lower section 15. A wedge bushing 16 is threaded on the upper end portion of the upper barrel section 14 and is provided with an external downwardly and inwardly inclined surface 17. A shoe member 18 is threaded on the lower end of the tubing T and has an internal downwardly and inwardly inclined seat 19. The surface 17 of the bushing 16 is adapted to cooperate with the seat 19 to suspend or support the barrel 10 on the tube T and the cooperation of the surface 17 with the seat 19 provides an effective seal between the bushing 16 and the shoe member 18. The shoe member 18 on the lower end of the tubing T may have a socket 20 in its lower end. A tubular shell 21 may have its upper end threaded in this socket 20 to project downwardly from the member 18. The shell 21 surrounds the barrel 10 with suitable clearance and serves to protect the pump barrel. The shell 21 may enclose the major portion of the barrel and its lower end may be open to the well. The pump barrel 10 includes a coupling member 22 connecting its two sections 14 and 15. The lower portion of the upper section 14 may be threaded on the upper portion of the member 22.

The lower barrel section 15 is of less diameter than the upper section 14 and is threaded into a socket 23 in the lower end of the member 22. The coupling member 22 has a central longitudinal opening 24 provided with an annular downwardly facing shoulder 25. The lower section 15 of the barrel 10 is of substantial length and is provided at its lower end with a guide shoe 26. The shoe 26 has a central longitudinal opening 27 and an upwardly facing internal annular shoulder 28. A packing liner or packing and guide bushing 29 is preferably provided on the interior of the lower section 15 of the barrel 10. The bushing 29 may be sectional, as shown in the drawings, and is clamped between the shoulders 25 and 28. It is believed that it will be apparent how proper assembling or threading on of the coupling member 22 and the shoe 26 operates to clamp the packing bushing 29 against movement in the barrel section 15.

In the preferred pump structure illustrated in the drawings the plunger 11 is the displacing element of the pump being a differential plunger reciprocable by the sucker rod R extending longitudinally through the tubing T from the pump jack or pump operating means at the surface of the ground. The plunger 11 is an elongate tubular assembly extending longitudinally

through the barrel 10 and projecting from the lower end of the barrel. The plunger 11 includes an upper tubular section 30 operable longitudinally in the upper section 14 of the barrel 10. A ported connection is provided to connect the upper plunger section 30 with the rod R. The connection includes a collar 31 threaded on the upper end portion of the section 30. The lower end of the collar 31 forms a downwardly facing shoulder 32. A threaded socket 33 is provided in the upper end of the collar 31 and the collar has a longitudinal opening 34 directly communicating with the longitudinal opening 35 of the plunger section 30. A connecting member 36 is threaded on the usual pin 37 on the lower end of the rod R and the member 36 has a threaded pin 38 on its lower end threaded into the socket 33. The member 36 is provided with an opening 39 having its lower end in communication with the opening 34 and the opening 35. Ports 40 in the wall of the member 36 place the upper end of the opening 39 in communication with the interior of the barrel 10. The upper section 30 of the plunger 11 carries sealing or packing means for providing a fluid seal between the plunger and the interior of the upper barrel section 14. Sleeves 41 surround the upper plunger section 30 between the shoulder 32 and a nut 42 threaded on the lower portion of the plunger section 30. The series of sleeves 41 is clamped between the nut 42 and the shoulder 32. The sleeves 41 are provided with vertically spaced external annular grooves 43. The grooves 43 are adapted to carry liquid which forms a liquid seal between the interior of the barrel section 14 and the sleeves 41 to form a seal between the plunger and the barrel.

The plunger 11 includes a lower section 44 operable in the lower portion of the barrel section 14 and extending through the lower barrel section 15. The plunger section 44 is tubular having a central longitudinal opening 45. The cages of the valves 12 and 13 connect the sections 30 and 44 of the plunger 11 as will be hereinafter described. The lower plunger section 44 extends through and slidably cooperates with the guiding and packing bushing 29. In practice the bushing 29 is of substantial length to have extensive sealing cooperation with the plunger section 44 and to effectively guide the lower end portion of the plunger in the barrel 10. The lower plunger section 44 projects downwardly beyond the lower end of the barrel section 15 and its lower end is open to receive the fluid from the well.

A stop or projection may be provided on the lower end of the plunger section 44 to cooperate with the lower end of the shoe 26. In the form of the invention illustrated in the drawings this stop is in the form of nuts 46 threaded on the lower portion of the section 44. The projection 46 is adapted to cooperate with the lower end of the shoe 26 when the pump is run into the tubing T on the sucker rod R and when it is desired to flush out the tubing T or remove the pump from the tubing. It is to be understood that the projection 46 does not engage the shoe 26 during the formal reciprocation or operation of the plunger 11. From the above description of the plunger 11 it will be seen that the plunger is guided and sealed about at vertically spaced zones within the barrel 10. It is to be noted that the lower section 44 of the plunger which extends into the upper section 14 of the barrel 10 is materially smaller in diameter than the opening of the barrel section 14 thus providing a chamber 75

C in the barrel which constitutes the displacement chamber of the pump.

The valve 12 is carried by the plunger 11 to prevent the escape or downward flow of the fluid from the chamber C through the opening 45 during the down stroke of the plunger 11, whereby fluid in the chamber C is displaced upwardly from the chamber to flow through the valve 13 into the tubing T. A connecting member 47 is threaded on the upper end of the plunger section 44 and has an upwardly projecting pin 48. An opening 49 extends vertically through the member 47 and communicates with the opening 45. The valve 12 includes a valve seat 50 on the upper end of the pin 48 and a ball or valve proper 51 for cooperating with the seat 50. A cage 52 is threaded on the pin 48 to clamp the seat 50 in place and to prevent the loss or displacement of the valve 51. The cage 52 has a chamber 53 in which the ball or valve 51 operates and ports 54 place this chamber 53 in communication with the displacement chamber C. In practice the cage 52 may be of substantial length and may be provided with a central longitudinal opening 55 whose lower end is in communication with the ports 54.

The valve 13 is the carrying valve of the pump and operates during the up stroke of the plunger 11 to retain or trap the fluid displaced into the opening 35 from the chamber C and to raise this fluid and the column of fluid in the tubing T. The upper valve 13 includes a seat 56, a ball or valve proper 57 for cooperating with the seat 56 and a cage 58 for the valve 57. The seat 56 may be provided on the upper end of the cage 52 to surround the upper end of its opening 55. The ball or valve 57 is adapted to seat downwardly on the seat 56 to close the upper end of the opening 55. The cage 58 is threaded on the upper end portion of the cage 52 and has a shoulder 59 engaging the seat 56 to hold it in position. A chamber 60 is provided in the cage 58 to carry the valve 57. A connecting member 61 is threaded on the lower end part of the upper plunger section 30 and the cage 58 is threaded on the member 61. The above described nut 42 may serve to lock the connecting member 61 in place. A central longitudinal opening 62 in the member 61 communicates with the opening 35 in the plunger section 30 and has its lower end in communication with the valve chamber 60. A ported baffle 63 is provided on the member 61 at the lower end of the opening 62 to prevent the valve 57 from closing the lower end of the opening 62 during the flow of fluid upwardly through the opening. The cage 58 and the connecting member 61 may have cooperating sealing surfaces 64 which engage to provide a fluid tight seal when the ports are properly assembled.

In the operation of the pump illustrated in Figs. 1 to 8, inclusive, and Fig. 12 of the drawings the pump parts may be assembled as shown in the drawings and the member 36 may be threaded on the pin 37 to secure the plunger 11 to the rod R. The shoe 26 is adapted to engage the projection 46 to support the barrel 10 on the plunger. Thus the barrel 10 is carried by the plunger which in turn is secured to the rod R so that the pump may be run through the tubing T on the rod. When the pump reaches its operating position the barrel 10 is adapted to project downwardly through the opening in the shoe 18 and the surface 17 is adapted to cooperate with the seat 19 to support or suspend the barrel in its final position. The cooperation of

the surface 17 with the seat 19 also provides a seal between the barrel 10 and the shoe 18. With the bushing 16 seated in the shoe 18 the pump is in condition for operation. It may be desirable to seat or position the pump so that the lower end 5 of the barrel 10 is spaced some distance above the level L of the liquid in the well as shown in Fig. 1 of the drawings. If the pump is set in this manner the lower portion of the lower plunger section 44 is alternately dipped into and drawn 10 from the liquid in the well as the plunger reciprocates.

During the up stroke of the plunger 11 the valve 57 cooperates with its seat 56 to lift the liquid in the opening 35 and to raise the column 15 in the tubing T. During the upward stroke of the plunger 11 a reduced pressure develops in the displacement chamber C. This reduced pressure is caused by the upward movement in the chamber C of the parts 52, 58, 61, 41, etc., of the plunger which are of larger diameter than the plunger section 44 and their upward movement in the plunger C creates the reduced pressure. This reduction in pressure in the chamber C results in opening of the valve 51 and the inflow of fluid 20 from the well through the opening 45. Assuming that the plunger 11 begins its upward stroke from a position where its lower end is submerged in the liquid of the well, liquid is drawn through the opening 45 into the chamber C during the initial 25 phase of the upward movement of the plunger. When the lower end of the plunger section 44 emerges from the liquid in the well, gas from the well is drawn through the opening 45 into the chamber C. Thus a quantity of liquid is first 30 drawn into the chamber C and a quantity of gas is then drawn into the chamber C during each up stroke of the plunger 11.

When the plunger 11 begins its down stroke the valve 51 first closes and the gas in the chamber C 40 is compressed. As the downward movement of the plunger continues the gas in the chamber C is compressed until the pressure on the gas is sufficient to unseat the valve 57 whereupon the gas and then the liquid are displaced from the chamber C through the openings 55 and 62 into the tubing T. From the above it will be seen that the pump of the present invention is operable to pump or obtain a relatively large amount of gas with respect to the quantity of liquid pumped 45 in a manner which eliminates the possibility of gas locks in the pump chamber when the pump is in operation. The plunger 11 described above and reciprocating in the barrel 10 is under a fluid pressure or head during the up stroke as well as the down stroke. The tubing T is likewise under a continuous head or down pressure. Thus the weight of the column of fluid in the tubing T is divided so that a part of the weight is on the tubing and a part of the weight is on the rod R 50 eliminating the slack or play in the tubing when the plunger is moving upwardly and eliminating the slack in the rod R during the down stroke of the plunger. As there is no slack or play in the rod R or the tubing T the pump may be operated at a comparatively high rate of speed to provide a greater production and there is a minimum of emulsification of the oil because of whipping of the rods, etc.

The valves 12 and 13 are both carried by the 70 reciprocating plunger 11 so that there is little or no danger of sand or other solid matter accumulating in the valves to interfere with their free operation. The portion of the plunger projecting from the lower end of the barrel 10 75

operates to break up any accumulation of solid matter at the intake of the pump and the reciprocation of the plunger in the body of liquid at the intake of the pump removes a quantity of the 5 gas from the liquid. When it becomes desirable to flush out the tubing T the reciprocation of the pump rod R is suspended and the rod is raised so that the projection 46 engages the shoe 26 to lift the barrel 10. Thus the barrel 10 may be 10 raised with the rod R to lift the surface 17 from the seat 19. This freeing of the bushing 16 from the shoe 18 allows the tubing to be flushed out. When it becomes desirable to remove the pump from the well the rod R is merely raised so that 15 the projection 46 engages the shoe 26 to cause the barrel 10 to be moved upwardly with the plunger 11 and the rod R whereby the entire pump is drawn upwardly through the tubing T without necessitating the withdrawal of the tubing 20 from the well.

The invention contemplates the interconnecting of several pumps of the character described above. Figs. 9 to 11, inclusive, and Fig. 13 illustrate the pump described above and a second 25 pump of the same character associated to be operable by the single operating rod R and to produce or deliver the fluid through the single tubing T. The two or more pumps may be spaced apart vertically along the tubing T as found 30 necessary. In the drawings the protective shell 21 of the upper pump is provided at its lower end with a coupling 66. Tubing T¹ is threaded to the coupling 66 and extends downwardly to the second or lower pump. The tubing T¹ may be of 35 the same diameter as the tubing T and may be of any length. A shoe or coupling member 18^a is threaded at the lower end of the tubing T¹. The member 18^a may be identical with the member 18 except that its opening and seat 19^a are smaller 40 than the opening and seat of the member 18. The barrel 10^a of the second or lower pump carries at its upper end a bushing 16^a having an inclined surface 17^a for cooperating with the seat 19^a. A protective seal 21^a is threaded to the 45 shoe or member 18^a to extend downwardly and enclose the barrel 10^a of the second pump. The barrel 10^a, the plunger 11^a and the valves of the second or lower pump may be of the same construction and operation as the corresponding elements 50 of the upper pump. The projecting lower end of the plunger 11^a extending from the lower end of the barrel 10^a is adapted to receive the fluid from the well as shown in the drawings. A coupling 75 connects the rod R¹ with the lower end of the plunger section 44 of the upper pump. Ports 76 are provided in the coupling to place the opening 45 in communication with the tubing T¹. Thus the inlet or receiving opening 45 of the upper pump is in communication with the interior of the tubing T¹. The rod R¹ extends 60 downwardly through the tubing T¹ to the plunger 11^a. The pin 37^a on the rod R¹ may be threaded into a socket 77 in the member 38^a. Thus the barrels 10 and 10^a are interposed in or are carried 65 by the tubing T—T¹ and the plungers 11 and 11^a of the pumps are carried by the rod R—R¹ to be operated simultaneously.

The pumps shown in Figs. 9 to 11, inclusive, and Fig. 13 operate in the same manner as the above described single pump except that the lower 70 pump discharges into the tubing T¹ and the upper pump receives the fluid from the tubing T¹ and discharges into the tubing T. The two interconnected pumps may be readily operated simultaneously by the single rod R and produce or deliver 75

the fluid through the single tubing T—T¹. The two pumps may be raised by means of the rod R—R¹ to permit the flushing of the tubing T—T¹ and may be run into and withdrawn from the tubing on the single rod. 5

Having described only typical preferred forms and applications of my invention, I do not wish to be limited or restricted to the specific details herein set forth, but wish to reserve to myself any variations or modifications that may appear 10 to those skilled in the art or fall within the scope of the following claims:

Having described my invention, I claim:

1. A well pump for use in a tubing having a seat comprising, a tubular barrel to be lowered through the tubing, the barrel having a part to cooperate with the seat and having an upper portion and a lower portion of reduced internal diameter, a tubular plunger reciprocable in the barrel and comprising an upper portion operating in the upper portion of the barrel and a reduced lower portion operating in the lower portion of the barrel and extending into the upper portion of the barrel to leave a chamber therein, the plunger having a surface exposed to the downward force exerted by the column of fluid in the tubing, the effective area of said surface being larger than the cross sectional area of the chamber whereby said force may move the plunger downwardly during its down stroke to displace the fluid from the chamber, means on the upper portion of the plunger for shiftably sealing with the interior of the upper portion of the barrel, means in the lower portion of the barrel sealing about the lower portion of the plunger, there being a port in the plunger placing the passage therein in communication with the chamber, the lower end of said passage being adapted to receive the fluid, a valve on the lower portion of the plunger operable to close the passage therein during the down stroke of the plunger, and a valve carried by the upper portion of the plunger operable to close communication between the passage therein and the chamber during the up stroke of the plunger, the valves being located one above the other. 30

2. Well pumping apparatus comprising, a tubing, a shoe on the lower end of the tubing, a barrel inserted through the tubing and having a projection for cooperating with the shoe to be supported by the tubing, a tubular plunger reciprocable in the barrel and projecting from its lower end to receive fluid, there being a chamber in the barrel and a port in the plunger placing its interior in communication with the chamber, valves on the plunger above and below the port governing the passage to effect a pumping action during reciprocation of the plunger, and a part on the projecting lower portion of the plunger engageable with the barrel whereby the plunger may carry the barrel through the tubing. 50

3. Well pumping apparatus comprising, a tubing, vertically spaced pumps each comprising a barrel, and a plunger reciprocable in the barrel, the uppermost pump comprising a part cooperating with the tubing to suspend said pump, and a shell around its barrel, the lower pump comprising a part cooperating with said shell to support said lower pump on the shell, an operating rod extending through the tubing and connected with the plunger of the upper pump, and a rod connecting the plungers of the pumps. 65

4. Well pumping apparatus comprising, a tubing, vertically spaced pumps each comprising a barrel, and a plunger reciprocable in the barrel, 70

the uppermost pump comprising a part cooperating with the tubing to suspend said pump, and a shell around its barrel and carrying the barrel of the lower pump, an operating rod extending 5 through the tubing and connected with the plunger of the upper pump, and means connecting the plungers of the pumps.

5. A well pump for use in a well having a tubing comprising, a barrel to be carried by the tubing, 10 a tubular plunger reciprocable in the barrel and projecting from the lower end of the barrel to receive fluid, the plunger having an upwardly facing surface exposed to the head of fluid in the tubing, the interior of the barrel comprising a 15 chamber through which the plunger extends, the cross sectional area of the chamber being less than the area of said surface whereby the hydrostatic pressure in the tubing may assist in moving the plunger downwardly during its down stroke, 20 means connected with the plunger for reciprocating the same, a valve carried by the plunger operable to admit fluid from the plunger to the chamber during the up stroke of the plunger and closed during the down stroke of the plunger and located 25 to move through the chamber during said strokes, and a valve carried by the plunger allowing the passage of fluid from the chamber upwardly through the plunger during the down stroke of the plunger and closed during the up stroke of 30 the plunger.

6. An elongate well pump for use on a tubing comprising, a tubular barrel to be suspended from the tubing and having an upper portion and a lower portion of less diameter than the said upper portion, a tubular plunger reciprocable in the barrel and shiftably sealed with the walls of said portions at longitudinally spaced points, the interior of said barrel between said points forming a chamber, the plunger having a surface exposed 35 to the downward force exerted by the column of fluid in the tubing, the effective area of said surface being larger than the cross sectional area of the chamber whereby said force may assist in moving the plunger downwardly during its down 40 stroke to displace the fluid from the chamber, an operating rod connected with the plunger to reciprocate the same, a valve carried by the plunger to move vertically in the chamber and operable to govern communication between the fluid admitting 45 lower portion of the plunger and the chamber, and a valve carried by the plunger governing communication between the fluid discharging upper portion of the chamber and the chamber.

55 7. A well pump for use on a tubing comprising, a tubular barrel, a differential tubular plunger reciprocable in the barrel, there being a chamber in the barrel from which the fluid is displaced upwardly through the plunger during the down 60 stroke of the plunger, vertically spaced ports in the plunger having communication with said chamber, the plunger having a surface exposed to the downward force exerted by the column of fluid in the tubing, the effective area of said surface being larger than the cross sectional area of the chamber whereby said force may move the plunger downwardly during its down stroke to displace the fluid from the chamber, a downwardly seating valve on the plunger controlling the lower port to allow flow of fluid through the lower portion of the plunger to the chamber, and a downwardly seating valve on the plunger controlling the upper port to allow the flow of fluid upwardly through the upper portion of the 65 plunger.

8. A well pump for use on a tubing comprising, a tubular barrel to be connected with the tubing, a differential tubular plunger reciprocable in the barrel and projecting from the lower end of the barrel to receive the well fluid, there being a chamber in the barrel from which the fluid is displaced upwardly through the plunger during the down stroke of the plunger, the plunger having a surface exposed to the downward force exerted by the column of fluid in the tubing, the effective area 10 of said surface being larger than the cross sectional area of the chamber whereby said force may move the plunger downwardly during its down stroke to displace the fluid from the chamber, vertically spaced ports in the plunger having 15 communication with said chamber, a downwardly seating valve on the plunger controlling the lower port to govern the fluid flow through the lower portion of the plunger, and a downwardly seating valve on the plunger controlling the upper 20 port to govern the fluid flow through the upper portion of the plunger.

9. A well pump for use with a tubing comprising, a tubular barrel to be connected with the tubing and having an upper portion and a lower 25 portion of reduced internal diameter, means for connecting the barrel with the tubing, a tubular plunger reciprocable in the barrel and comprising an upper portion operating in the upper portion of the barrel and a reduced lower portion 30 operating in the lower portion of the barrel and extending into the upper portion of the barrel to leave a chamber therein, there being a port in the plunger communicating with the chamber, the plunger having a surface exposed to the 35 downward force exerted by the column of fluid in the tubing, the effective area of said surface being larger than the cross sectional area of the chamber whereby said force may move the plunger downwardly during its down stroke to 40 displace the fluid from the chamber, the lower end of the plunger being adapted to receive the well fluid, a valve in the lower portion of the plunger operable to close the same during the down stroke of the plunger, and a valve carried 45 by the upper portion of the plunger above the first mentioned valve operable to close communication between the plunger and the chamber during the upstroke of the plunger.

10. A well pump for use on a tubing comprising, a barrel to be connected with the tubing and having an upper portion and a lower portion of reduced internal diameter, a tubular plunger reciprocable in the barrel and comprising an upper portion operating in the upper portion of the 50 barrel and a reduced lower portion operating in the lower portion of the barrel and extending into the upper portion of the barrel to leave a chamber therein, the plunger having a surface exposed to the downward force exerted by the column of fluid in the tubing, the effective area of said surface being larger than the cross sectional area of the chamber whereby said force may move the plunger downwardly during its down stroke to 55 displace the fluid from the chamber, a ported valve cage connecting said portions of the plunger, a valve in said cage operable to close the passage in the lower portion of the tubular plunger during the down stroke of the plunger, and a valve in said cage operable to close communication between the chamber and the passage in the upper portion of the plunger during 60 the upstroke of the plunger.

11. A well pump for use in a tubing comprising, a tubular barrel having an upper portion and 70

75

5 a lower portion of reduced internal diameter, means for mounting the barrel in the tubing, a tubular plunger reciprocable in the barrel and comprising an upper portion operating in the upper portion of the barrel and a reduced lower portion operating in the lower portion of the barrel and extending into the upper portion of the barrel to leave a chamber therein, the plunger having a surface exposed to the downward force exerted by the column of fluid in the tubing, the effective area of said surface being 10 larger than the cross sectional area of the chamber whereby said force may assist in moving the plunger downwardly during its down stroke to 15 displace the fluid from the chamber, means carried by the upper portion of the plunger for shiftably sealing with the interior of the upper portion of the barrel, there being a port in the plunger placing the passage therein in communication 20 with the chamber, the lower end of said passage being adapted to receive the fluid, a valve in the lower portion of the plunger at said port operable to close the passage therein during the down stroke of the plunger, and a valve carried by the 25 upper portion of the plunger operable to close communication between the passage therein and the chamber during the up stroke of the plunger.

12. Well pumping apparatus comprising, a tubing, vertically spaced pumps each comprising a 30 barrel, and a plunger reciprocable in the barrel, the uppermost pump comprising a part co-operating with the tubing to suspend said pump, means for connecting its plunger with an operating member, and a shell around its barrel, the 35 lower pump comprising a part cooperating with said shell to support said lower pump on the shell, the plunger of the lower pump being connected with the plunger of the uppermost pump so that the pumps operate in series.

13. A well pump for use in a well having a tubing, said pump comprising, a barrel to be connected with the tubing, a differential plunger reciprocable in the barrel, exposed to the head pressure in the tubing and adapted to receive 15 fluid from the well at its lower end, the interior of the barrel comprising a chamber through which the plunger passes, the plunger having a longitudinal passage with its upper end in communication with the chamber, the lower end of the passage being adapted to receive fluid from the well, a valve on the plunger at the upper end

of its passage for controlling communication between the chamber and the fluid receiving end of the plunger passage, the area of the plunger exposed to the downward force of the head pressure in the tubing being greater than the cross sectional area of the chamber whereby said head pressure may assist in moving the plunger downwardly during its down stroke, and a valve on the plunger governing communication between the chamber and the fluid discharging end of the 10 plunger.

14. A well pump for use in a well having a tubing comprising, a barrel to be lowered into the tubing, means for mounting the barrel in the tubing, a tubular plunger reciprocable in the barrel and operable to receive fluid at its lower end, the plunger presenting a surface subject to the downward pressure exerted by the column of fluid in the tubing, the interior of the barrel comprising a chamber through which the plunger extends, the cross sectional area of the chamber being less than the area of said surface, a valve on the plunger movable through the chamber and governing communication between the chamber and the fluid admitting end of the plunger, and a valve on the plunger governing communication between the chamber and the fluid discharging end of the plunger.

15. A well pump comprising, a tubular barrel to be suspended from a tubing, a tubular plunger reciprocable in the barrel and adapted to receive fluid through its lower end, means on the exterior of the plunger sealing with the barrel, means on the interior of the barrel spaced below the first mentioned means sealing with the plunger, the said means being spaced so that there is a chamber formed in the pump between said means, the plunger having a surface exposed to the downward force exerted by the column of fluid in the tubing, the effective area of said surface being larger than the cross sectional area of the chamber whereby said force may move the plunger downwardly during its down stroke to displace the fluid from the chamber, a valve carried by the plunger to have movement in the chamber and governing communication between the chamber and lower portion of the tubular plunger, and a valve carried by the plunger governing communication between the chamber and the fluid discharging upper portion of the plunger.
